UNITED STATES PATENT OFFICE.

JACOB BONSHIRE, OF REDKEY, INDIANA.

DESIGN FOR A JAR-LID CLAMP.

SPECIFICATION forming part of Design No. 28,052, dated December 14, 1897.

Application filed October 30, 1897. Serial No. 656,972. Term of patent 14 years.

To all whom it may concern:

Be it known that I, JACOB BONSHIRE, a citizen of the United States, residing at Redkey, in the county of Jay and State of Indiana, have invented and produced a new and useful and original Design for Jar-Lid Clamps; and I do hereby declare the following to be a full, clear, and exact description of the same, reference being had to the accompanying drawings, forming a part thereof.

This design relates to a jar-lid clamp designed to be used in clamping a lid to a jar, and is illustrated in the accompanying drawings, wherein like letters of reference indicate corresponding parts in the several views, and in which--

Figure 1 is a top plan view of a clamp, showing my design. Fig. 2 is a side elevation. Fig. 3 is a perspective view, and Fig. 4 is an end view.

In the drawings, A designates a straight portion having curved ends forming the oppositely-extending loops B. The straight portion A and the loops B are formed in the same horizontal plane. Depending from the loops

B are the straight portions C, which are arranged in parallel relation. Extending inwardly from the portions C are the offset portions D, and extending from the offset portions in opposite directions are the ends E, which are arranged parallel with each other.

The leading feature of my design consists of the straight portion provided with the oppositely-extending loops, the parallel portions depending from the loops, the inwardly-extending offset portions, and the end portions extending in opposite directions from the offset portions.

Having thus described my invention, what I claim as new, and desire to secure by Letters Patent, is--

The design for a jar-lid clamp, substantially as herein shown and described.

In testimony whereof I affix my signature in presence of two witnesses.

JACOB BONSHIRE.

Witnesses:

C. ROY HATHAWAY,
